CLAIM

The ornamental design for a spatula used to make dental prosthesis, as shown and described.

DESCRIPTION

FIG. 1 is a perspective view of a spatula used to make dental prosthesis, showing our new design;

FIG. 2 is a right side elevational view thereof, the undisclosed left side elevational view being a mirror image;

FIG. 3 is a top plan view thereof;

FIG. 4 is a bottom plan view thereof;

FIG. 5 is a front view thereof;

FIG. 6 is a rear view thereof;

FIG. 7 is a cross-sectional view along line 7—7 of FIG. 2; and,

FIG. 8 is a cross-sectional view along line 8—8 of FIG. 2.
